UNITED STATES PATENT OFFICE

JAMES TILLOTSON, JR., OF JAMESTOWN, AND JAN STRENG, OF NEW YORK, N. Y., AS-SIGNORS TO KOLSTER RADIO, INC., OF NEW YORK, N. Y., A CORPORATION OF NEW JERSEY

DESIGN FOR A RADIOCABINET

Application filed September 25, 1931. Serial No. 41,227. Term of patent 3½ years.

To all whom it may concern:

Be it known that we, JAMES TILLOTSON, Jr., and JAN STRENG, both citizens of the United States, and residents, respectively, of Jamestown, in the county of Chautauqua and State of New York, and New York, in the county and State of New York, have invented a new, original, and ornamental Design for Radiocabinets, of which the following is a specification, reference being had to the accompanying drawings, forming a part thereof.

Fig. 1 shows a front elevational view of the radiocabinet.

Fig. 2 shows a side view of the radiocabinet. Fig. 3 shows a top view of the radiocabinet.

We claim:

The ornamental design for a radiocabinet, as shown.

In witness whereof we hereunto subscribe our names this 11th day of Sept., 1931, and this 15th day of Sept., 1931, respectively.

JAN STRENG.
